PORTABLE POWER-DRIVEN NUT SETTER

Filed Oct. 14, 1948

UNITED STATES PATENT OFFICE

2,607,252

PORTABLE POWER DRIVEN NUT SETTER

Ernest H. Shaff, Spring Lake, Mich., assignor to
Keller Tool Company, Grand Haven, Mich., a
corporation of Michigan

Application October 14, 1948, Serial No. 54,456

2 Claims. (Cl. 81—57)

1

The present invention relates to portable power operated nut runners and more especially to power operated nut runners embodying an impact clutch of the so-called kick-out type operative to drive the nut home upon the completion of the free running operation.

The primary object of the invention is to provide as a part of the nut driving means a magazine providing an elongated chamber for receiving and retaining a stack of nuts to be driven in a manner such as to feed the nuts one by one to bolts or similar threaded elements.

A further object is to provide in a portable power driven nut runner a nut magazine for receiving and retaining a stack of nuts, together with means of a simple and practical character for supporting and driving the magazine in the application of the nuts one by one to the work.

Another object is to provide a novel and effectual means for insuring delivery of the nuts one by one from the magazine.

Other objects and advantages of the invention will become apparent from the following detailed description taken in conjunction with the accompanying drawings in which:

Figure 1 is a vertical section through a nut setter constructed in accordance with the present invention.

Fig. 2 is a fragmentary section on an enlarged scale through the forward end portion of the nut setter illustrated in Fig. 1.

Fig. 3 is a transverse section taken substantially in the plane of line 3—3 in Fig. 1.

Fig. 4 is a fragmentary section similar to Fig. 2 but illustrating the application of a nut to a threaded element.

Fig. 5 is a transverse section taken substantially in the plane of line 5—5 in Fig. 4.

While the invention is susceptible of various modifications and alternative constructions, there is shown in the drawings and will herein be described in detail the preferred embodiment, but it is to be understood that it is not intended thereby to limit the invention to the form disclosed, but it is intended to cover all modifications and alternative constructions falling within the spirit and scope of the invention as expressed in the appended claims.

As illustrated in the drawings the exemplary form of the invention is shown embodied in a portable pressure fluid actuated tool comprising an elongated generally cylindrical main housing 8 having a rotary pneumatic motor 9 therein for driving a shaft 10. As shown, the motor 9 comprises a casing formed by a sleeve 11 and end plates 12 and 13, and a radially slidably vane type

2

rotor 14 eccentrically disposed within the sleeve 11. The rotor 14 is mounted on the shaft 10 which extends axially therethrough. The ends of the shaft 10 project through the end plates 12 and 13 and are supported in bearings 15 and 16.

Adjacent the rear end of the tool is disposed a valve mechanism 18 for control of the admission of pressure fluid to actuate the tool. Pressure fluid is supplied to the tool from any suitable source (not shown) by way of an axial supply passage 19 and a fitting 20 received in the outer end thereof. The valve 18 is disposed in a bore 21 in a valve block 22. It includes a sleeve 24 closely fitted in the bore 21 and a plunger 25 shiftable axially within the sleeve. Upon opening the valve 21 pressure fluid is admitted to drive the rotor 14 by way of suitable ports (not shown) in the valve block 22 and the end plate 13.

The valve 18, as shown, is operated by means of a spring lever 26 conveniently disposed along the underside of the housing 8 for actuation by the fingers of an operator using the tool. The lever 26 is secured at its forward end to the housing 8 as by a screw 28. Adjacent the rear end of the lever 26 is fixed a pin 29 which engages the outer end of the valve plunger 25. The latter and the sleeve 24 extend outwardly from the valve block 22 through an opening 30 in the housing 8.

To permit ready alignment of the bore 21 in the valve block 22 and the housing opening 30 when the tool is assembled and thus facilitate its manufacture, the valve block 22 is fashioned to be slipped axially into the housing 8, no rotation thereof being required. The valve block is clamped in proper position within the housing against the end plate 13 by an end cap 31 which is screw threaded into the outer end of the housing 8 and which bears against the block 22.

Spent pressure fluid is exhausted from the motor casing through exhaust ports 32 in the sleeve 11, into a generally annular space 34 partially surrounding the sleeve 11 and thence through the end plate 12 by way of ports 35, and annular channel 36 and ports 38.

In accordance with my invention, the tool is provided at one end with a head, generally designated 40, in which is mounted a combined nut containing and driving mechanism whereby a stack of nuts is supported for feeding movement in a direction transversely of the axis of the drive motor. The mechanism includes a magazine, generally designated 41, mounted for axial as well as rotational movements and providing an elongated chamber of polygonal cross section for receiving the nuts, the magazine being driven

from the motor through the medium of an impact or kick-out clutch, engaged and disengaged as permitted by axial movements of the magazine.

In the present instance, the head 40 is formed in major part by an extension 42 of the tool housing 8 and by a cap 43 screw-threaded into the lower open end of the extension 42. Journaled in the head is a sleeve 44 constituting a hollow drive shaft and having rigid therewith a bevel gear 45 meshing with a bevel pinion 45a on the motor shaft 10. The hollow drive shaft 44 is thus disposed at an angle to the axis of the motor shaft 10 being herein approximately 70 degrees with respect to such shaft.

The magazine 41 is, in the instant embodiment, formed in part by a second hollow shaft 60 fitting snugly into the drive shaft 44 for rotational and axial movements therein. This inner hollow shaft is of substantially greater length than the outer shaft or sleeve so that its opposite ends project substantially beyond the ends of the sleeve, and at its lower end has a nut driving socket 61 threaded thereon.

The shaft 60 is arranged to be driven from the drive shaft 44 through the medium of a kick-out clutch 56, presently to be described, and to adapt the shaft to the reception of a stack of nuts it is provided with an inner liner in the form of an elongated tubular member 64 having a bore of polygonal cross section, herein shown as hexagonal. The tubular member 64 is loosely received within the driven shaft 60 but is held against rotational movement relative thereto through the medium of the socket member 61. To this end, the liner member has a projection 65 formed on its lower end which is adapted to be received within a recess 66 in the socket 61. The latter has a bore of polygonal cross section aligned with the polygonal bore of the tubular member, the projection and recess being so arranged as to maintain the two hexagonal bores in the socket member and liner member in proper angular relation to insure the passage of the nuts from the liner member into the socket member.

The magazine thus comprised of the hollow driven shaft 60, the tubular liner member 64 and the socket member 61 is completed by a cap 67 having a lower open end fitting slidably over the upper end of the shaft 60 and disengageably connected thereto by any suitable means as by a bayonet type connection 68. The cap is adapted to receive a coiled compression spring 70 bearing at one end against the outer closed end of the cap and at its other end against the uppermost nut in the stack contained within the magazine.

The kick-out clutch 56 providing the driving connection between the two shafts 44 and 60 comprises an upper annular clutch block 56a rigid with the lower end of the drive shaft 44, and a lower annular clutch block 56b encircling the lower portion of the driven shaft 60 and therefore rigid with the magazine. So that a nut may be driven "home" when it becomes tight on a bolt or the like, the clutch elements 56a and 56b are provided with interengaging teeth having sloping side faces to permit the teeth of the driving clutch element 56a to slide over and then re-engage those of the driven clutch element 56b thus creating a hammering action for application to the nut. The clutch elements 56a and 56b are urged into engagement by force applied by the operator in pressing the tool

against the work, the inner hollow shaft 60 on which the driven element 56b is mounted having a loose running fit within the hollow driving shaft 44 thus permitting the necessary axial movement. Outward movement of the shaft 60 together with the clutch element 56b and the socket 61 is limited by engagement of the outer face of the clutch element 56b with the inner face of the housing cap 43.

Means is provided to hold back the nuts in the bore of the tube 64 to prevent them from being forced outwardly therefrom by the action of the spring 70 except when applied to a threaded element. In the present instance, a catch element 75 is provided for this purpose on the socket 61. The catch element 75 is in the form of a dog pivotally mounted intermediate its ends on a spring 76 disposed about the lower end of the socket 61 and received in an axially extending slot 78 provided therefor in the socket. The spring 76 is in the form of a split ring and is received in a peripheral groove 79 disposed about the socket 61.

Since the threaded end of a bolt or the like projecting from a workpiece is generally longer than the thickness of the nut to be applied thereto, the next following nut must be prevented from being threaded onto the bolt along with the first nut. This is accomplished in the present instance, by locating the projection 75a of the catch 75 a short distance from the end of the socket member. However, such distance is short enough so that the nut can be reached by the bolt B. When the first nut has been applied to the bolt, screw threading of the nut thereon draws the nut downwardly through the bore in the socket 61. Such movement causes the projection 75a of the catch element 75 to be forced outwardly. It will be noted upon reference to Fig. 2 that the inner edge of the catch 75 is flush with the surface of the bore in the socket 61 and thus rides against the nuts passing therethrough. Outward movement of the projection 75a tends to pivot the catch element 75 on the spring 76 but such motion is resisted by engagement of the upper portion of the catch element 75 with the next adjacent nut. This causes the spring 76 to be forced outwardly resulting in application of pressure to the second nut by the upper portion of the catch element so that it is held back and prevented from following the first nut downwardly through the bore in the socket 61. After the first nut has been applied and the tool removed, the spring 76 and the catch element 75 move back to normal position thus letting the nuts down so that the next one can be applied to the next threaded element.

In the use of the tool, a stack of nuts is placed within the magazine with the lowermost nut in engagement with the nose of the dog 75 and therefore disposed a short distance from the end of the socket member 61. The cap 67 is then applied so that the spring 70 exerts a downward pressure on the stack of nuts.

In the application of a nut to a bolt or the like, the operator exerts downward pressure on the tool, causing the driven shaft 60 to move upwardly to carry the lower clutch block 56b into engagement with the upper clutch block 56a on the drive shaft 44. The motor is then set in operation by actuation of the lever 26, causing the nut to be driven onto the threaded element until sufficiently tight to resist further rotation, whereupon the driving connection becomes temporarily disengaged.

gaged and then immediately re-engaged to drive the nut home with a series of blows.

It will be seen that the tool may be easily adapted for use with nuts of various sizes and shapes by replacing the liner tube 64 and socket member 61 of the magazine with similar parts of appropriate shapes and dimensions.

I claim as my invention:

1. In a portable power driven nut setter, the combination of a hollow tool head, a tubular drive shaft journaled in said tool head and held against axial movement therein, an elongated magazine for receiving a plurality of nuts in axially stacked relation, said magazine being disposed within said tubular drive shaft with one end terminating in a nut driving socket, said tool head having upper and lower aligned openings therein with the socket end of the magazine extending through the lower opening and the opposite end of said magazine projecting through the upper opening, and a kickout clutch in said tool head having an annular driving clutch element rigid with the lower end of the drive shaft and a driven clutch element rigid with said magazine, said magazine being axially shiftable with respect to said drive shaft and said tool head in response to engagement and disengagement of said clutch.

2. In a portable power driven nut setter, the combination of a magazine for receiving a plurality of nuts in axially stacked relation and terminating at one end in a nut driving socket having a longitudinal slot therein intersecting its bore, and a retainer for holding the nuts in said magazine and operative to release the nuts one at a time therefrom, said retainer including a

dog and a spring supported on said socket and yieldably and pivotally mounting said dog intermediate its ends in said socket slot with the inner edge of said dog substantially flush with the wall of the socket bore, said dog having an inwardly projecting nose portion adjacent the outer end thereof normally disposed for engagement with the lowermost nut in said magazine, the nose portion of said dog being shaped so that upon forceful withdrawal of the lowermost nut from the magazine the lower portion of the dog will be cammed outwardly against the action of said spring and the upper end portion of said dog will be simultaneously moved into frictional engagement with the succeeding nut in the magazine to retain the same therein.
